ATTORNEYS.

UNITED STATES PATENT OFFICE.

NELSON HUGHES, OF PORTLAND, OREGON, ASSIGNOR TO HUGHES MANUFACTURING COMPANY, OF PORTLAND, OREGON, A CORPORATION.

DRAW-GAGE AND CUTTER.

No. 896,385.

Specification of Letters Patent. Patented Aug. 18, 1908.

Application filed December 23, 1907. Serial No. 407,785.

To all whom it may concern:

Be it known that I, NELSON HUGHES, residing at Portland, in the county of Multnomah and State of Oregon, have invented 5 certain new and useful Improvements in Draw-Gages and Cutters, of which the following is a specification.

My invention relates to certain new and useful improvements in draw gages and 10 leather cutters and the like and it primarily has for its object to provide a device of this character that wholly obliterates the chances of destroying the accuracy of the gage through grinding of the knife by different 15 operators.

My invention also has for its object to provide a knife blade of the largest possible cutting edge capacity, thus performing more work with each grinding.

20 My invention also has for its object to provide a gage and cutter which will have an increased range of work and in which the parts are so arranged and combined as to be easily controllable and operable and will 25 effectively serve its intended purposes.

Generically, my invention comprises a body provided with a hand gripping portion which body portion includes a clamping device for clamping a gage and a cutter carrying bar to hold them in their respective positions and finger engaging means for operating the clamping mechanism to secure and release the bars as occasion may require. 30 A cutter and a disk gage are carried by the cutter bar and gage bar respectively and serve to co-act in cutting the leather.

In its more subordinate nature, my invention comprises certain novel details of construction, combination and arrangement 40 of parts, all of which will be first described in detail and then be specifically pointed out in the appended claims, reference being had to the accompanying drawings, in which:

Figure 1, is a perspective view of my invention. Fig. 2, is a central, vertical longitudinal section thereof. Fig. 3, is a detail section on the line 3—3 of Fig. 2. Fig. 4, is a detail perspective view of the trigger mechanism. Fig. 5, is a detail section and elevation of the rotary cutter and the gage or shearing disk which co-operates therewith.

Referring now to the accompanying drawings in which like letters and numerals of reference indicate like parts in all of the 55 figures, 1 represents the body member which

is preferably formed of metal and is provided with an internal chamber 1^x and a pair of arms 1^d that are countersunk into the handle 1^e and secured thereto by a screw 1^f, as indicated.

The body 1 is provided with a clamping head 1^a having semi-circular bearings 1^b—1^c to co-operate with the clamping block 2^e that has corresponding semi-circular bearings 2^a—2^b respectively. The clamping head 60 and block are apertured to permit passage of an eye bolt 7 which projects through the head 2 and receives an adjusting nut 8.

Within the chamber 1^x of the body portion 1 of my device, the eye bolt 7 projects 70 and has its eye portion 7^a held in co-operative relation to the eccentric pin 9^b of the trigger member 9, the pin 9^b projecting through the eye portion 7^a and being held by a groove bearing that is provided with an 75 annular groove 9^c, as shown, and the bearing 9^a is of cylindrical form and projects through an aperture in the lower wall of the body member 1, it being held in place by a screw 10 that passes through the body 1 and 80 lies in the groove 9^c.

3 designates the gage bar which is provided with a scale 3^a of any suitable graduation and carries at one end a gage disk 4 that is secured in place by a screw 4^a, as clearly 85 shown in Fig. 1 of the drawings.

The gage disk 4 also serves in connection with the shearing knife 6 to cut the leather 11, indicated in dotted lines in Fig. 5. The rotary knife 6 is of thin flat steel and is held 90 onto the knife bar 5 by a screw 6^a co-operating with the collar 6^b.

In the practical operation and use of my invention, the gage bar 3 is first set to the desired distance from the body 1 and the 95 knife bar 5 correspondingly adjusted so that the knife 6 and disk 4 will engage one another, as indicated in Fig. 5, after which, the trigger member 9 is turned from the dotted position shown in Fig. 3 to the position shown in 100 Fig. 2 and thus draws up on the head 2 bringing it tightly against the head 1^a to clamp the bars 3 and 5.

While the construction illustrated in the accompanying drawings herein described shows a preferable form of my invention it is manifest that such construction may be further modified and details thereof varied without departing from the scope of the appended claims.

110

From the foregoing description, taken in connection with the accompanying drawings, it is thought the complete construction, operation and many advantages of my invention will be readily understood by those skilled in the art to which the invention appertains.

What I claim is:—

1. A device comprising in combination with adjustable sliding gage and cutting bars, a gage disk journaled on the gage bar and a rotary knife journaled on the cutter bar.
2. A draw gage and cutter comprising in combination with a clamp headed body having a hand gripping portion, gage and cutter bars coöoperating with such clamp headed body member and means carried by said gage and cutter bars for cutting the material operated upon.
3. The combination with a body member having a clamp head and a clamp block coöperating therewith, rods passing between said clamp head and clamp block, means carried by the body member and projecting through the clamp head and block for drawing the clamp block against the clamp head.
4. The combination with a body member having a clamp head and a clamp block coöperating therewith, rods passing between said clamp head and clamp block, means carried by the body member and projecting through the clamp head and block for drawing the clamp block against the clamp head, said means comprising an eye bolt passing through the clamp head and block and a trigger member carried by the body portion and having an eccentric pin projecting through the eye of the eye bolt.
5. The combination with a body member having a clamp head and a clamp block coöperating therewith, rods passing between said clamp head and clamp block, means carried by the body member and projected through the clamp head and block for drawing the clamp block against the clamp head, said means comprising an eye bolt passing through the clamp head and block, and a trigger member carried by the body portion and having an eccentric pin projecting through the eye of the eye bolt, and cutting mechanism carried by said bars.
6. In a device of the class described, a

body member having an internal chamber and a clamp head, a clamp block coöoperating with said clamp head, means carried by the body portion and projecting through said clamp block for securing the clamp block against the clamp head, means clamped between said clamp block and said clamp head, and clamp engaging means for coöperating with said clamping means to operate the same.

7. A device of the class described, comprising a body portion provided with a chamber, a handle secured to said body portion and forming a closure for one end of said chamber, said body portion having an aperture in one of its walls, a trigger member having a cylindrical pivot portion projecting through said aperture, means coöperating with said cylindrical portion and the body member for holding said trigger member in position, a clamp head formed with said body portion and forming a closure for the other end of its chamber, a clamp block coöperating with said clamp head, a rod clamped between said clamp head and clamp block, means coöperating with said trigger member and said clamp block for securing the same against the clamp head.

8. A device of the class described, comprising a body portion provided with a chamber, a handle secured to said body portion, and forming a closure for one end of said chamber, said body portion having an aperture in one of its walls, a trigger member having a cylindrical pivot portion projecting through said aperture, means coöperating with said cylindrical portion and the body member for holding said trigger member in position, a clamp head formed with said body portion and forming a closure for the other end of its chamber, a clamp block coöperating with said clamp head, a rod clamped between said clamp head and clamp block, means coöperating with said trigger member and said clamp block for securing the same against the clamp head, a second rod clamped between said clamp rod and clamp head and coöperative means carried by said rods for acting upon the material to be operated upon.

NELSON HUGHES.
